ABSTRACT

The beam of charged particles of a luminescent screen tube is displaced under the combined action of two orthogonal scans, the spot being constrained to follow guiding strips formed on the luminescent screen surface and responsive to the position of said spot by modulating the control of one of the two scans by means of an error signal which is deduced from the indications supplied by the guiding strips. By means of continuous correspondence control, the spot is initially guided over an entire line entrance surface towards the beginning of the path to be followed by said spot before it passes onto the screen proper.

METHOD AND APPARATUS FOR ELECTRON BEAM CONTROL

This invention applies to luminescent screen tubes in which light signals are generated by impact of a beam of charged particles, the displacement of which is carried out by a combination of two orthogonal scans obtained respectively by means of two electromagnetic or electrostatic fields which are also orthogonal.

Among the tubes of this type, mention can be made of the ion tubes or the cathode-ray tubes such as, for example, those employed in oscilloscope screens or more generally for the reproduction of images in television.

In tubes of this type, the exact position of the spot at a given moment is defined only by the two horizontal and vertical deflection control systems, which entails the need to ensure that the trace of the spot on the screen, or television image, is subjected to a certain number of inevitable distortions under the action on the one hand of interference and on the other hand of inherent defects in the electronic system for controlling the two deflections.

If the particular case of color television is now examined, it is observed that the above-mentioned defects have even more serious consequences in regard to the quality of the image than is the case in monochrome television.

In fact, it is known that the tubes in widest use in color television are of the so-called "shadow-mask" type. In tubes of this type, the luminescent coating which lines the internal wall of the screen is made up of over a million luminescent dots, or luminophors, which are grouped together in triads each comprising one red luminophor, one blue luminophor and one green luminophor. At a distance of approximately 15 mm behind the screen, there is placed a mask pierced with a number of holes corresponding to the number of triads of luminophors, namely approximately 400,000. The mask is placed in such a manner as to ensure that its holes are in register with the centers of each triad. Moreover, the neck of the picture tube contains three electron guns each corresponding to the transmission of information relating to one color and positioned within the tube in such a manner as to ensure that each electron gun is in direct line of access, through the holes of the mask, only to those luminophors which correspond to its color.

It is consequently apparent that any distortions which are inherent in monochrome systems have repercussions which in this case are increased by the existence of three beams relatively displaced in space and that these are attended by a number of further consequences which arise from the fact that any deviation from the theoretical operation of the mask produces an error in the restoration of the color sensation.

To these numerous defects can finally be added the fact that there is a loss in the shadow mask of 80 percent of the beam energy which is stopped and converted to undesirable heat at the time of passage of the beam through said mask as well as the considerable difficulties involved in the technological development of a tube of this type.

It has already been proposed (as disclosed in particular in French Pat. No. 948,653) to control automatically the position of the spot on the screen of a television tube by comparing at each instant the real state of

the scanning field with a standard reference field and by correcting the instantaneous position of the spot by means of a control loop driven by a signal obtained by comparison with an arbitrarily fixed reference value which must correspond to a predetermined position of the spot with respect to the fixed field.

Since the intensity of the spot is modulated as a function of time for the reproduction of an image, the error signal obtained is "merged" into the spectrum of the image modulation signal and cannot in practice be separated from the signal just mentioned, thereby making any correction illusory even when making use of the device for varying the gain of the correction amplifier as described on page 3, lines 21 to 32 of French Pat. No. 948,653.

Moreover, the system as described is also inoperative by reason of the fact that it presupposes perfect coincidence between the theoretical field represented by the reference conductive strips and the real field of the beam. In point of fact, even if a relative displacement of very small value occurs at the start of each line, the error which is accumulated after a number of lines results in displacement of the spot with respect to its reference field and the method becomes inoperative. In an alternative mode of execution (page 3 lines 33 to 49), it has certainly been proposed to accumulate the error signals read at the end of each line by making use of these signals themselves as vertical deflection signals. Unfortunately, this improvement is inapplicable in practice by reason of the dissymmetry which is present in all systems of optoelectronic deflection systems.

This invention is directed to a method for guiding the beam of a luminescent screen tube which makes it possible to overcome most of the defects mentioned in the foregoing by ensuring strictly accurate displacement of the spot along the lines of one of the two scanning fields, and which permits in particular excellent reproduction of the color images while being much more simple to manufacture than the shadow-mask tubes.

This method of guiding the beam of charged particles of a luminescent screen tube consists in displacing said beam under the combined action of two orthogonal scans, in controlling the spot to be followed in dependence on guiding means carried by the screen and responsive to the position of said spot by modulating the control of one of the two scans aforementioned by means of an error signal deduced from the indications supplied by said guiding means, and in first guiding said spot by continuous control over the entire surface of a line entrance zone before said spot passes onto the screen proper, towards the beginning of the path which it is intended to follow.

The lines of the horizontal scan are defined on the screen by guiding means which the spot is constrained to follow as virtual "rails"; distortion is therefore no longer possible in the vertical scan, irrespective of any interference which may also be present or of defects which may be encountered either in the electronic circuits or the optical system of the tube. This result is obtained by virtue of the fact that the guiding means located on the screen are responsive to the passage of the spot, to which they react by emitting a continuous or periodic current (which can in any case be only a fraction of the beam itself) or an electromagnetic radiation. Inasmuch as the intensity or amplitude of the frequency of the signal thus collected is characteristic of the difference between the real position and the theoretical

position (defined by the guiding means) of the spot at each instant, there is thus formed an error signal which serves to modulate the vertical scanning integrator control. The controlling action thus obtained is very fast by reason of the low L/R time constant which is chosen for the vertical scanning control.

In accordance with one essential property of the method which forms the subject of this invention, the spot is previously guided before each line entrance on the luminescent screen proper towards the beginning of the rectilineal path which it is intended to follow. To this end, a line entrance zone extending downwards over the entire left-hand portion of the screen (which cannot be seen by the viewer) is lined on the inside wall of the picture tube with beam-guiding means, the signals of which are emitted under the action of the spot and applied to the vertical deflection control so as to constrain the spot to move towards the line entrance. In accordance with an interesting feature of this arrangement, the gain of said position control is increased by increasing the intensity of the beam during the last part of the line blanking signal. The presence in accordance with the invention of a line entrance zone over which the spot is guided by continuous control each time the beam returns to the beginning of its intended path makes it possible to overcome by simple means the major difficulties which were explained earlier and which arose in the cited prior art from the inevitable dissymmetry of the optoelectronic deflection system.

The method according to the invention applies generally to all types of screen scanning which are employed in practice. However, for reasons of simplicity, the following description will be limited to the method of scanning which is the most widely adopted in television, namely to two deflections respectively in the vertical and horizontal directions, in which the spot scans successively from left to right (as seen by the viewer) and from top to bottom a series of straight or so-called horizontal lines although these latter are in fact very slightly inclined downwards from left to right. However, it must remain clearly understood that the ensuing description is not intended to imply any limitation and the transpositions which are necessary in order to apply the invention can be made without any difficulty by those who are versed in the art.

In the particular and very important case in which, as a result of constant-pitch spatial distribution of the beam-guiding means, the signal collected is periodic and has a theoretical frequency f in respect of a theoretical horizontal linear scanning velocity v , the difference between said value f and the measured real instantaneous value f' is utilized in accordance with the invention for the purpose of forming an error signal which is applied in this instance to the horizontal scanning control, with the result that the spot is caused to move along each line at the constant theoretical velocity v . In accordance with this very important characteristic feature of the method according to the invention, the distortions of the horizontal scan are therefore also corrected irrespective of the causes of such distortions. This possibility which is offered by the invention is of considerable significance since it permits the construction of tubes having very wide angles of deflection and therefore of much smaller overall length, this being achieved by means of very simple correction circuits.

Finally, there are at the present time a certain number of cases, especially for the reproduction of color images, in which the luminescent screen tube employed contains a number of electron guns in which the beams 5 are intended to travel along parallel traces on the screen. In this case, the method according to the invention is perfectly applicable in the following manner: one of the beams, or so-called master beam, is caused to follow the guiding means carried by the screen and 10 the other beams, or so-called slave beams, are constrained to follow the displacements of the master beam; to this end, the centering permanent magnets are simply set once and for all before the tube is put into service and in such a manner as to ensure that all the beams emitted by the different electron guns penetrate into the zone in which the magnetic scanning fields are set up as parallel as possible to the axis of the deflecting system and as close as possible to said axis.

This invention is also directed to a luminescent screen which is essentially provided over the entire luminescent surface proper of said screen with a series of guiding strips having a width substantially equal to the diameter of the spot and each corresponding to one of the lines of one of the scanning fields, said strips being formed by a succession of zones modulated in width with a pitch p_1 , any positional deviation of the spot with respect to one of said strips resulting in an error signal which produces by integration the signal which 20 controls the other scan in order to cause displacement of said spot at each instant while strictly centered on the edge of said strip.

The use of guiding means distributed with a constant pitch gives rise to an error signal constituted by at least 35 one amplitude-modulated carrier frequency. By virtue of this essential property, said error signal can be very readily distinguished from the video modulation, thereby providing a simple and elegant solution to the difficulties which, in the devices of the prior art herein-40 before described, resulted in confusions between the error signal and the video signal.

The rectilineal horizontal guiding strips are formed by a succession of zones modulated in width with a pitch p_1 and the scansion of the spot at the horizontal 45 velocity v along each strip consequently produces a signal having a frequency $f_1 = v/p_1$ and whose amplitude of greater or lesser value is characteristic of the position of the spot with respect to said strips; it is accordingly necessary to use only the amplitude variations of 50 said signal as an error signal to control the vertical scan. In one particular case of appreciable significance, said modulated strips are constituted by a series of broken lines having a pitch p_1 . In all cases, the modulation 55 of the collected signal at the frequency f_1 very considerably facilitates its identification.

In the most common designs, the scanning system is the type employed in ordinary television receivers, namely a combination of a horizontal deflection and a vertical deflection. In this particular case, the guiding strips are rectilineal and horizontal on the screen.

When the guiding strips are simple, the control is of the unilateral type and the error signal which results from the instantaneous deviation between the theoretical position of the spot defined by the guiding strip and its real position accordingly produces the vertical scanning control signal directly by integration so as to cause the spot to move horizontally at each instant while re-

maining strictly centered on the edge of the guiding strip.

When the guiding strips are made up of a conductive metal, said strips themselves serve as electrodes for the partial return of the master beam. In other words, it is the more or less large fraction of the beam current intensity which traverses said strips and which is therefore characteristic of the vertical position of the spot with respect to said strips which is employed as an error signal. The second fraction of the master beam current is closed on the return electrode which is common to all beams which may be employed.

Broadly speaking, the collected signals derived from the reactions of the guiding strips to the scanning travel of the spot can be of different types: in particular, they may consist of a fraction of the beam current which is closed on said conductive strips, or an electromagnetic radiation such as ultraviolet radiation, for example, which is detected by a photoelectric detector and converted into a current having a frequency which is characteristic of the identity of the signal; in some cases also, the guiding strips are formed of a material which gives rise to a strong emission of secondary electrons which can be collected by means of a special electrode located within the tube in the vicinity of the luminescent screen, the current constituted by said secondary electrons being then employed as an error signal.

In all the examples hereinbefore described, the guiding means are constituted by a single modulated strip which is marked on the screen at the location of each horizontal scanning line. In other words, in these examples, control of the spot of the master beam which is made to follow these strips is carried out in a unilateral manner and it is well known in the technique of correspondence control systems in general that a method of this type gives rise to practical difficulties, especially when the intensity of the beam is modulated.

It is for this reason that, in other embodiments of luminescent screen tubes according to the present invention, the guiding means are constituted by a series of double strips, that is to say in which each strip has an upper guide and a lower guide spaced at a distance from each other which is smaller than the diameter of the spot in order that this latter may always be in contact with at least one of the two guides at the time of scanning. In these embodiments, the error signal employed which results from the positional deviation of the spot of the master beam with respect to said double strips is constituted:

either by the difference in the amplitudes of the signals corresponding respectively to the upper guide and to the lower guide of each strip, in which case said error signal is employed for modulating the vertical scanning control signal at a higher or lower level depending on whether it is either positive or negative, thus resulting in a much easier and much more accurate control since the error signal is alternately positive and negative;

or by the ratio of said amplitudes which must be maintained equal to unity, which offers the additional advantage of eliminating any component arising from the modulation of the beam intensity.

In accordance with a first alternative embodiment, the two guides of each double strip are constituted by continuous electrically conductive metallic strips; each of these two guides receives a variable fraction of the beam current as a function of the vertical position of the spot and the difference between these two current

fractions collected in two separate return circuits is used to constitute the error signal which serves to modulate the input signal of the vertical scanning control integrator.

- 5 In another alternative embodiment, the two guides of each double strip are made up of width-modulated strips, the width of the upper guide of each strip being modulated with the pitch p_1 and the width of the lower guide of each strip being modulated with the pitch p_2 .
- 10 Under these conditions, when the spot of the master beam scans the double strip at the velocity v of horizontal linear displacement, said spot produces two families of signals having the respective frequencies $f_1 = v/p_1, f_2 = v/p_2$, the respective amplitudes of said signals being representative of the exact vertical position of the spot at each instant. It is therefore only necessary in accordance with the invention to form in accordance with known means the difference or the ratio of said amplitudes in order to constitute the error signal which serves to modulate at a higher or lower level the input signal of the vertical scanning control integrator. In this alternative embodiment, the collected signal which has two frequency components f_1 and f_2 is collected in the form of a current only and the two guides of each strip 15 — when they are conductive — are connected electrically to a single and common electrode for collecting the signal. In the most frequent case, the signal having the frequency components f_1 and f_2 is constituted simply by that fraction of the master beam current which is closed on the upper and lower portion of the guiding strips within the electrode which is connected to said strips, the other current fraction being closed on another electrode and this latter can advantageously be the return electrode which is common to the luminescent screen proper.

In further embodiments, it is an advantage to form said continuous strips of a substance which gives rise either to the emission of an electromagnetic radiation which is detected by a photoelectric cell located in the vicinity of the picture tube neck or of a substance which gives rise to the emission of two secondary electron currents having frequencies f_1 and f_2 which are accordingly collected on an electrode placed in the vicinity of the screen. In either case, the current obtained 20 in the single circuit contains frequency components f_1 and f_2 which can readily be identified and are employed for constituting the error signal as hereinbefore described.

50 In accordance with a further important feature of the present invention, the luminescent screen tube is provided within the entire line entrance zone on which the spot impinges each time the beam returns with means for guiding said spot towards the start or entrance of the line which is to be precisely described by said spot. 55 In the most common case of a rectangular television screen with horizontal and vertical scanning, said line entrance zone extends over the entire height of the screen on the left portion of this latter as considered from the viewing side but outside the luminescent surface proper and concealed from the viewer by the casing of the television set.

60 In a first embodiment, said guiding means of the line entrance zone consist of continuous surfaces which are responsive to the presence of the spot and located on each side of the extensions of each horizontal and rectilinear guiding strips which constitute two sets of electrodes. Under the action of the spot, the surfaces afore-

said generate currents i_1 in the case of that portion which is located above the guiding strip and i_2 in that portion which is located below said guiding strip. It is therefore readily understood that, by making use of the difference between these two currents i_1 and i_2 which are collected at the two sets of electrodes as an error signal for modulating the vertical beam sweep, it is possible to obtain a fast vertical deviation of the beam in order that the spot should be very rapidly brought into the vicinity of the entrance of the line which it is intended to describe.

In another embodiment of said line entrance zone, the guiding means consist of non-continuous surfaces. The zone which is located on each side of the extensions of each horizontal rectilinear strip comprises "blocks" of surfaces arranged in alternate sequence and having a pitch p_1 above said strips and a pitch p_2 below these latter. Thus, as the spot of the master beam travels at the horizontal velocity v , so said spot produces signals having a frequency $f_1 = v/p_1$ and $f_2 = v/p_2$ such that the difference or ratio of amplitudes can be utilized as an error signal for modulating the vertical sweep or scan of the beam and the other fraction of the master beam is closed in a loop, for example by the common electrode of the luminescent screen.

For the reproduction of monochrome images, it is certainly possible to contemplate modes of application of the invention which consists of a single electron gun, and in which the guiding spot is used at the same time for reproduction of the image; however, such a constructional design is not without difficulty since it calls for the presence of a minimum signal which impairs the black. In the majority of cases, the invention is carried out by means of two electron guns, the beams of which are constrained to travel in parallel relation, the spot of the first gun or master beam being caused to travel on the non-luminescent guiding strip and the spot of the second gun or slave beam being caused to travel on a luminescent strip of the screen.

However, it is in its applications to the reproduction of color television images that the present invention finds one of its most interesting and advantageous applications. The invention is accordingly directed to a luminescent screen tube which is distinguished by the fact that the horizontal guiding strips are each associated with a triplet of three continuous horizontal and rectilinear strips of luminescent material each corresponding to one of the primary colors, the tube being provided with four electron guns in which the first or so-called master gun emits the guiding beam which is caused to follow the horizontal and rectilinear guiding strips and in which the three other electron guns or so-called slave guns each correspond to one of the three primary colors and emit beams which are caused to follow the displacements of the master beam so that the corresponding spots should travel in a direction parallel to the spot of the guiding beam while strictly scanning each of the three luminescent color strips.

A tube of this type is infinitely more simple to produce than the shadow-mask tubes which have most frequently been employed up to the present time and makes it possible to obtain a reproduction of color images of considerably superior quality with much more simple means. In particular, it can very readily be ensured in accordance with the invention that the three electron guns corresponding to the light signals of the three primary colors are constrained to follow the dis-

placements of the master gun in such a manner that their three spots should follow on the screen rectilinear paths which are parallel to those of the spot of the master gun: it is in fact only necessary to carry out before 5 putting the tube into service a permanent adjustment of the centering permanent magnets placed around the neck of the picture tube by producing action on the internal pole-pieces in such a manner that the deflections produced by these latter should cause the four beams 10 corresponding to the four electron guns to penetrate into the zone in which the magnetic scanning fields are applied as parallel as possible to the axis of the deflecting system and as close as possible to said axis. Providing that this condition is satisfied, the deflections applied to the master beam by means of the orthogonal magnetic fields are automatically followed by the three 15 slave beams. Finally, it is important to note that the luminescent screen tube in accordance with the invention ensures compatibility with respect to black and white transmissions; it is only necessary for this purpose, as in the case of shadow-mask tubes, to adjust once and for all the ratio of currents of the three electron guns.

In a particular embodiment of the luminescent screen 20 tube for reproduction of color television images, the device is simplified by making use of only two electron guns. The first gun accordingly performs the function of master gun and emits the guiding beam, the spot of which is caused to follow the rectilinear and horizontal 25 guiding strips on the screen; the other electron gun alone carries out, as a result of an additional instantaneous vertical deflection imparted thereto with respect to its position of dependence on the master gun, a 30 point-to-point scanning of the three luminescent strips 35 corresponding to the three primary colors. This result is obtained by means of a ternary sequence which controls simultaneously a pair of electrodes for additional vertical deflection provided in the tube at the level of the deflecting coils as well as the successive switching 40 of the three luminance signals. This form of construction results in a tube of more simple design but it remains apparent that, with respect to the previous embodiment in which three electron guns are each specialized in one color, there is a loss of a certain quantity 45 of information and that the overall restitution of the image is of inferior quality inasmuch as a loss of definition occurs in the horizontal direction.

Finally, and in a general manner, the luminescent 50 screen tube in accordance with the invention for the reproduction of color television images is wholly suited to the method of scanning which is usually employed in practice and known as alternate-field scanning or double interlacing. This method of scanning has been developed in order to make it possible without increasing the quantity of information transmitted, to eliminate effects of flicker which resulted from an excessive time interval between two consecutive images. In a system of this type, scanning of horizontal lines is carried 55 out by dividing each image into two half-images, each consisting of only even-numbered lines or odd-numbered lines. Many alternative forms of construction can be employed for adapting the luminescent screen tubes according to the present invention to the aforesaid method of interlaced scanning; particular mention can nevertheless be made of two such forms of construction which appear to be among the most attractive.

In a first embodiment, the horizontal guiding strips are each associated with a triplet of color strips and are each constituted by two guides. The upper guide and the lower guide of the strip having the order n are each formed by a series of broken lines having respective pitches p_1 and p_2 ; the same upper and lower guides of the guiding strip having the order $n + 1$ are formed by broken lines having reverse pitches, that is to say respectively p_2 and p_1 . This arrangement permits ready identification of the even-numbered lines and the odd-numbered lines by control of the master beam; at the time of scanning of each of these two half-fields as in any case defined by methods which are already well-known, from the synchronizing signals of the transmitter, one color triplet out of two is scanned by the three color electron guns.

In a second embodiment, the horizontal guiding strips are associated with a plurality of luminescent color strips which are either more or less than three in number and all the guiding strips are identical. Additional deflections with respect to the dependence on the master electron gun are then imposed on the three color beams so that, at the time of each half-field scan, only a certain number of color strips are scanned by the beams.

A point which is finally worth noting is that, when the luminescent screen tubes according to the invention are employed, it can prove very useful to distinguish the master beam from the slave beam with unerring certainty, if only to prevent the guiding strips from being traversed by one of the slave beams which may accidentally have been "trapped" by one of said strips. In accordance with the invention, it is consequently an advantage to modulate the beam of the master gun at a high frequency which is preferably higher than that of the video signal. The indications collected under the effect of the reaction of the guiding strips to the spot are accordingly collected at said characteristic modulation frequency if the master beam is in fact concerned; in the contrary case, no signal is transmitted to the vertical scanning control loop.

A better understanding of the invention will in any case be gained from a perusal of the following description which gives a number of examples in connection with the practical application of the method employed for guiding the beam of a luminescent screen tube and also relates to the luminescent screen tube which makes use of said method. Reference will be made in the description to the accompanying drawings, in which;

FIG. 1 illustrates one form of construction of a television screen in accordance with the invention, in which the guiding strips are double and continuous;

FIG. 2 is an enlarged view showing the top portion of FIG. 1;

FIG. 3 is a diagram of the electronic circuit which is associated with the construction of FIGS. 1 and 2;

FIG. 4 is a sectional view taken along line Z-Z' of FIG. 5 and shows the arrangement, within the neck of the picture tube, of the four electron guns and beam-centering magnets;

FIG. 5 is a sectional view taken along line X-Y of FIG. 4;

FIG. 6 shows one example of application of the invention to a luminescent screen in the case in which the guiding strips are double and electrically continuous but spatially modulated with two pitches p_1 and p_2 ;

FIG. 7 shows one example of application of the invention to a luminescent screen tube in the case in which the guiding strips are double, are electrically non-continuous, have electromagnetic radiation emission, and are modulated in space with two pitches p_1 and p_2 ;

FIG. 8 shows the electronic circuit for applying the vertical scanning correction in the case of a guiding device according to the diagram of FIG. 7;

FIG. 9 shows the electronic circuit associated with a television screen according to the invention in the case in which the control of the master spot in the line entrance zone is enhanced by increasing the beam intensity at the start of a line;

FIG. 10 is a diagram of the electronic circuit which is associated with a color television tube having four electron guns and provided with a circuit for controlling the horizontal scanning velocity;

FIG. 11 is a diagram of the electronic circuit which is associated with a television tube and in which the beam of the master electron gun is modulated at high frequency;

FIG. 12 illustrates the principle involved in scanning the screen of a color television tube equipped with a master gun and a slave gun;

FIG. 13 is a diagram of the electronic circuit associated with the tube of FIG. 12;

FIG. 14 illustrates the principle involved in scanning the screen of a color television tube in two interlaced half-fields, said tube being equipped with three slave guns and one master gun, wherein each pair of triplets comprises one luminescent strip and one common guiding strip;

FIG. 15 shows one form of construction of a color television screen for scanning in two interlaced half-fields, wherein each guiding strip having alternate pitches is associated with a color triplet;

FIG. 16 is a diagram of the electronic circuit associated with the tube of FIG. 15;

FIG. 17 illustrates one form of construction of a color television screen for scanning in two interlaced half-fields, wherein each guiding strip is associated with two identical color triplets.

In FIG. 1, there is shown very diagrammatically the contour 1 of the screen proper of a television tube having a given number of horizontal scanning lines such as 2, 3, 4. The downward slope of these so-called horizontal lines has been purposely exaggerated in FIG. 1 and the number of lines 2, 3 and 4 has been limited to three for the sake of simplicity of the drawing but it remains wholly apparent that the angle of inclination of the horizontal lines is much smaller in practice and that the number of lines can be much higher without thereby departing from the scope of the invention. In accordance with the invention, the screen is divided into two sections in the vertical direction, namely a first section A located on the left of a vertical line X-X' and a second section B located on the right of said line. The section A will be designated throughout the remainder of this specification as the "line entrance zone"; the section B corresponds to the luminescent portion which consequently forms the screen proper as seen by the viewer.

In accordance with the invention, each line 2, 3 and 4 is materialized by double conductive strips which are deposited on the surface of the luminescent screen and each comprise an upper guide (2a in the case of strip

2, 3a in the case of strip 3 and 4a in the case of strip 4) and a lower guide (2b in the case of strip 2, 3b in the case of strip 3 and 4b in the case of strip 4). In the line entrance zone A which is shown in much greater detail in FIG. 2, the upper and lower guides of each horizontal guiding strip 2, 3 and 4 are extended by surfaces 5, 6, 7, 8, 9 and 10 which are each effectively joined to one of the guides of the guiding strips. Thus in the example of FIGS. 1 and 2, the surface 5 is joined to the guide 2a, the surface 6 to the guide 2b, the surface 7 to the guide 3a, the surface 8 to the guide 3b, the surface 9 to the guide 4a, the surface 10 to the guide 4b. The surfaces 5 to 10 are connected in pairs and in parallel to two conductors 11 and 12, each of which therefore corresponds in fact to the parallel connection of the upper guides 2a, 3a and 4a in the case of the conductor 11 and the lower guides 2b, 3b and 4b in the case of the conductor 12.

In FIGS. 1 and 2, there are shown in the form of small circles the positions of the spot corresponding to the master beam whilst the slave beams which may be employed have not been shown. In this example, control of the master beam in dependence on the rectilinear and horizontal trajectories defined by the control strips 2, 3 and 4 is obtained by means of the return currents of the master beam which pass through the conductors 11 and 12 at each instant as a function of the position of the point of impact of the master spot on the screen.

There can again be seen in the corresponding electronic circuit diagram of FIG. 3 the screen 1 of the luminescent tube 13, in which are also shown the vertical beam-deflection coils 14 and the horizontal beam-deflection coils 16. In the schematic diagram of FIG. 3, only the master gun 17 has been shown for reasons of simplicity. The horizontal deflection, that is to say the scanning of the different lines of the image, is carried out by means of the signal 18 which controls the saw-tooth generator 19. The pulses 18 are the line synchronizing pulses which are delivered by the emitter and well known in television techniques. The vertical sweep, also known as the field sweep or scan, is carried out by means of the integrator 20 constituted by an operational amplifier 21 and a feedback capacitor 22. The assembly 20 is reset to zero at each field under the action of the control of the field synchronizing pulses 23 which are delivered by the emitter onto line 24 and which release the normally-blocked transistor 25. All these arrangements are in any case very well known and widely employed in all orthogonal-deflection tubes.

The circuit shown in the schematic diagram of FIG. 3 further comprises a direct-current voltage source 26. The constant voltage V supplied by said source 26 is applied through the resistor 27 to the input of the integrator system 20 and determines the scanning velocity thereof in the vertical direction. This velocity is chosen so as to ensure that, in the absence of any control of the master spot by the guiding means in accordance with the invention, said spot should have a tendency to follow spontaneously a mean path which roughly corresponds to each horizontal line of the field and consequently to the inclination of these latter to the horizontal direction. The device of FIG. 3 finally comprises two resistors 28 and 29 by means of which are closed the currents of the master beam which pass through the conductors 11 and 12, said two resistors 28 and 29

being connected to ground. When currents pass through the conductors 11 and 12, a potential difference appears at the terminals of each of the resistors 28 and 29 and these two potential differences are applied to the input of the integrator 20 through two resistors 30 and 31 after one of these latter which corresponds to the resistor 28 has been reversed by the amplifier 32, the gain of which is equal to -1.

The operation of the devices of FIGS. 1 to 3 is accordingly as follows:

The current of the master electron beam emitted by the gun 17 of the cathode-ray tube 13 is closed on the conductors 11 or 12 depending on its point of impact on the screen 1. It is readily apparent that, if the spot is located at 33 in FIG. 2 at the start of a field, the master-beam current is closed on the electrode 11 and generates a voltage at the terminals of the resistor 28. On the contrary, if the spot appears at 34, the current is closed on the electrode 12 and generates a current within the resistor 29.

If the spot is located at 35, for example, and exactly centered on the interval between the electrode surfaces 5 and 6, the return current of the master beam is equally divided between the two resistors 28 and 29.

At each instant, the difference between the voltages appearing at the terminals of the resistors 28 and 29 aforesaid is therefore representative of the position of the spot with respect to one of the horizontal scanning lines.

The different polarities are adjusted in order that, if the spot appears at 33 at the entrance of the system (FIG. 2), the voltage which appears at the terminals of the resistor 28 of FIG. 3 produces action after reversal at 32 on the integrator 20 which increases its integration rate in such a manner that its output signal, after a further amplification at 36, will increase at a higher rate than under the action of the current alone within the resistor 27. This output signal is transmitted via the line 37 to the vertical deflection coils 14. As a result, the spot does not follow the path 33-38 but will move downwards more rapidly and reach 39, then 40. At this instant, the return current of the master beam is divided between the conductors 11 and 12 although of higher value in the conductor 12 than in the conductor 11 and the signal which appears at the terminals of the resistor 29 is of higher strength than the signal which appears at the terminals of the resistor 28, with the result that the difference between the two voltages as applied to the resistors 31 and 30 is in this case of opposite direction; the result thereby achieved in accordance with the invention is an error signal which is applied to the vertical sweep integrator 20 and delivers a control signal in the line 37 having a direction such that the beam has a tendency to move upwards with respect to the pattern of lines and moves from 40 to 35. When the beam has reached 35, the so-called line entrance zone A and the surfaces 5 and 6 have performed their functions and the spot 35 which is positioned exactly at the start of line 2 need only follow said line 2 in accordance with the same method of control while being guided by the two upper and lower guides 2a and 2b in much the same manner as veritable rails. In fact, whenever the spot exhibits any tendency to escape from the interval between the guides 2a and 2b, correction signals modify the integration rate of the integrator 20 in the appropriate direction for returning the spot exactly to the center of the interval between the guides 2a and

2b. The precision of guidance obtained depends only on the size of the spot and can be several times smaller in width than the diameter of this latter. The time constant of action can be of very low value, the inertia of the electron beam being negligible and the time constant L/R of the vertical deflection coils 14 can be as low in value as may be desired.

In accordance with the invention, the width of the guiding electrodes is completely different, depending on whether the location considered is either the line entrance zone in which the beam does not yet have any definite position after returning from the end of the following line or the line proper in which the beam is already pre-positioned within the interval between the two guides, in which slight instantaneous corrections are sufficient to maintain the beam within said interval. The zones which are not occupied by the guiding system can receive the different luminescent substances which are necessary for the formation of images.

As a result of the low inertia of the beam and of the control assembly, the line entrance zone aforesaid can correspond to a small portion of the width of the screen such as a few percent, for example; in the case of a tube having a width of 60 cm, said zone can be of the order of one centimeter.

In the example hereinbefore described, it has been assumed that, as a result of a distortion of sweep or of faulty adjustment of the integration rate of the integrator 20, for example, the spot which had previously traversed the first line from 41 to 42 (FIG. 1) then returned at 43 into the line entrance zone slightly below the following line 3; the correction then takes place immediately and the spot passes through the successive positions 44 and 45 so as to reach at 46 the start or entrance of the second line 3 which it will then be able to follow precisely.

When the spot comes to 47, the field-synchronizing pulse is applied and discharges the integrator, with the result that the spot is brought into the vicinity of 33, at which the cycle begins again.

In a simplified mode of execution, a unilateral control of the master beam is employed. To this end, the constant voltage source 26 is dispensed with, the rate of integration without correction of the integrator 20 being in that case zero and only one of the two systems of guiding electrodes is retained; in this case, the rectilinear guiding strips are simplified and are each constituted only by a single guide coinciding with each line and the line entrance zone only has one series of conductive surfaces such as the surfaces 5, 7 and 9, for example. In consequence, the correction signal derived from the line 11 is alone necessary since the correction control should always be in the downward direction; this control is discontinued as soon as the spot leaves the guiding electrode and is intensified as the surface which is covered by the guiding electrode increases. The control through the line 12 can in this case be dispensed with.

In a mode of execution of this type, the error signal resulting from deviation of the spot with respect to the strip which it is intended to traverse therefore produces directly by integration the vertical sweep control signal and the spot moves while remaining centered on one of the edges of said strip, depending on whether the guiding strips corresponding to channel 11 or channel 12 have been retained. As a set-off against its simplicity, a unilateral control system of this type is more sensitive

to interference and possible transients and, although it can naturally be employed, it consequently offers less reliable operation.

Referring to FIGS. 4 and 5, there will now be described the devices which are employed within the scope of the present invention to cause the beams of the slave electron guns to follow the displacements of the beam of the master electron gun. In FIG. 4 there is shown the neck 48 of the picture tube 13 and, in this example, four electron guns designated respectively by the references 17, 50, 51 and 52 are employed for producing the desired images on the screen. In FIG. 4, the tube is seen from above and the four electron guns 17, 50, 51 and 52 are located approximately in the horizontal mid-plane of the picture tube 13. The electron gun 17 performs the function of master gun and the three other electron guns 50, 51 and 52 perform the functions of slave guns. By means of the four magnetic centering systems formed by the five internal pole-pieces 53, 54, 55, 56 and 209, the beams derived from the four electron guns 17, 50, 51 and 52 are so adjusted that they arrive within the zone in which the magnetic field is produced by the deflecting coils and are as parallel as possible to the axis of the tube and as close as possible to this latter. Providing that this condition is satisfied, the four beams undergo the same electromagnetic deflections and their spots describe parallel paths on the screen. In FIG. 5 which is a sectional view taken along line X-Y of FIG. 4, there are shown the four permanent magnets 58, 59, 60 and 61, the magnetic circuits of which are closed on the external pole-pieces 210, 211, 212, 213, these latter being so arranged that the deflecting fields should have the desired direction and intensity within the air-gaps formed by the internal pole-pieces 53, 54, 55, 56 and 209 in order that the beams 216, 217, 218 and 219 derived respectively from the electron guns 17, 50, 51 and 52 should be deflected through the precise angle desired in the horizontal plane in order to make them parallel.

FIG. 6 shows a particular form of construction of the master-beam guiding means in accordance with the invention, in which each guiding strip is made up of two upper and lower guides modulated in space with respective pitches p_1 and p_2 . There is shown in FIG. 6 the line entrance zone A and the luminescent zone B proper of the screen, the construction shown being intended to correspond to the reproduction of color television images by means of the three-color process. To this end, the first two double lines 2 and 3 are each associated with a triplet of three luminescent strips designated respectively as 2b' or blue strip, 2r or red strip, 2v or green strip, 3b', 3r and 3v for the line 3. In accordance with the invention, the upper guide 2a of the strip 2 is provided with a certain number of cut-out portions such as the portions 62 and 63 having a pitch p_1 ; the lower guide 2b of the strip 2 has a certain number of cut-out portions 64, 65 and 66 having a pitch p_2 . Similarly, the cut-out portions of the surface A of the line entrance zone from areas 67 and 68 having a pitch p_1 above the line 2 and areas 69, 70 and 71 having a pitch p_2 below the line 2. Since the spot 72 of the master electron gun travels along the chain-dotted line 73 towards the entrance of line 2 and then on said line 2 itself, the three color beams corresponding to the three beams constrained to follow the master beam are so adjusted that their vertical spacing corresponds exactly to the spacing of the three color strips 2b', 2r and 2v

when the spot of the master beam is exactly centered on the line 2. This is the case in the third position shown in FIG. 6 in which can be seen the master spot 74, the green spot 75, the red spot 76 and the blue spot 77. In the case of the example of FIG. 6, the shaded guiding surfaces are continuous and the regulation can therefore be carried out, if in addition said surfaces are electrically conductive, by forming the error signal by means of the difference in amplitude of the currents having frequencies f_1 and f_2 which are produced within the guiding electrode 220 by reason of the fact that fractions of the current which are variable at each instant are closed on said electrode. The remaining portion of the master-beam current is closed on these portions which are left blank in FIG. 6 and correspond to another possible return path which is common, for example, with the return of the electrons of the red, blue and green beams which strike the respective luminescent portions of the screen. With regard to the method of control of the vertical position of the master beam, said method is the same as hereinbefore described.

Without departing from the scope of the invention, it is also possible to form the shaded surfaces shown in FIG. 6 by making use of a material which possesses high secondary electron emissivity (such as magnesium oxide, for example), the electrons being collected by a special auxiliary electrode placed for this purpose in the vicinity of the screen within the tube. The variation in frequency components f_1 and f_2 of the secondary emission current when the spot strikes the shaded or white portions is then employed as control signal and collected either in the circuit of the electrode 220 or in the circuit of the auxiliary electrode.

In the example of FIG. 7 in which the arrangements of FIG. 6 are again shown, the guiding strips 2 and 3 are constituted on the other hand by two upper and lower guides which still have the pitches p_1 and p_2 but are in this case non-continuous. In other words, these guides are made up of broken lines such as, for example, the lines 78, 79, 80, 81 and 82 which constitute the upper guide 2a of the strip 2 and the lines 83, 84, 85 having a pitch p_2 and constituting the lower guides 2b of the horizontal scanning line 2. Similarly, the line entrance zone A is made up of a certain number of "blocks" or surfaces which are cut-out to form portions of rectangles as designated by the references 86, 87, 88, 89 and 90 having a pitch p_1 in the case of the portion located above the scanning line 2 and 91, 92, 93 having a pitch p_2 in the case of the portion located below the line 2. These cut-out zones are isolated from each other and, in this example of execution, the detection of the error signal is performed by means of electromagnetic signals produced by the passage of the master spot over the surfaces aforementioned or the guiding strip lines. In the particular example herein described, said surfaces and said strip lines are advantageously formed of a material which is endowed with ultraviolet emissivity and the presence of this radiation in the vicinity of the tube neck is detected by means of a photoelectric device.

No matter what physical quantity may finally be employed (electromagnetic current or signal), the error signal is formed and employed by the circuit of FIG. 8. This figure again shows a certain number of elements which were already described in FIG. 3 and bear the same reference numerals. There is shown on the screen only one horizontal line, namely the line 2 provided with its means for guiding within the line entrance zone

A and on the luminescent screen B proper. There are shown within the neck 48 of the picture tube 13 the single master electron gun 17 and also the photosensitive detector 94 which collects the electromagnetic signals produced by the traverses of the spot along the guiding strips.

If the horizontal scanning lines are traversed by the master spot 72 at the linear velocity v , the photosensitive detector 94 receives a mixture of electromagnetic signals at frequencies $f_1 = p_1/v$ and $f_2 = p_2/v$. These signals are converted into a current which is amplified by the amplifier 95. Thereupon, said current is transmitted through two resistors 96 and 97 to two oscillating circuits 98 and 99 respectively tuned in one case to the frequency f_1 and in the other case to the frequency f_2 . This makes it possible without any risk of error to separate the portion having a frequency f_1 from the portion having a frequency f_2 in the overall signal received. The two corresponding currents are then rectified by the rectifiers 100 and 101 which are mounted in top-to-tail relation and the output current of which is delivered through the resistors 102 and 103. It is ensured by means of the top-to-tail assembly of the rectifiers 100 and 101 that a current which is finally proportioned to the difference in amplitudes of the two frequency components f_1 and f_2 is applied to the input of the vertical sweep integrator 20. After passing through the integrator 20, the same signal corrects by means of the line 37 the vertical deflection produced by the coils 14. In this manner, the spot 72 of the master beam is caused to follow the guiding strip 2 with strict precision and the three corresponding spots 75, 76 and 77 similarly traverse the three color strips 2v, 2r and 2b' along parallel paths on the screen.

By way of example, a luminescent screen for the reproduction of color television images for the European standard of 625 lines at 25 pictures per second would have a theoretical number of quadruplets equal to 575, taking into account the retrace time (quadruplets being constituted by a guiding strip and the three colored luminescence strips); in actual fact, this number is somewhat smaller, namely 525 quadruplets, for example; this makes it possible to form the necessary margins of the order of 4 percent around the screen. In the case of a tube having a useful picture height of 44 cm, the space between quadruplets is 0.8 mm; the fluorescent strips of each triplet can be separated if necessary by non-fluorescent intervals, thereby making it possible in this case for the spot to pass beyond said strips without impairing the purity of the colors. Similarly, in order to take into account variations in luminous efficiency, the different strips can have unequal widths such as, for example, 20/100 mm in the case of red, 15/100 mm in the case of blue and green and 15/100 mm for the control system. On the basis of these assumptions, a group of quadruplets consequently covers 80/100 mm including the margins. In the line entrance zone A, the luminance signal is clearly zero and only the spot corresponding to the master-gun beam is present.

There is shown in FIG. 9 an improved alternative form of the device of FIG. 8 in which control of the spot of the master beam is performed by means of an error signal defined by signals having frequencies f_1 and f_2 which are collected on the screen. In the embodiment of FIG. 9, the signals consist of a current of secondary electrons which are collected in the vicinity of the screen by an electrode (not shown) and are

represented by a current which is collected across the transformer 104. In this example, said electrode is brought by the source 105 to a positive voltage with respect to ground. The horizontal and vertical deflecting coils 16 and 14 are supplied from a power source 106 and the line scan is controlled by the sawtooth generator 19. The three chrominance electron guns 50, 51 and 52 which each correspond to one of the three primary colors are controlled by the matrix circuit 107 whilst the cathodes 108 of the electron guns aforesaid receive the luminance signal derived from the circuit 109. The grid of the master electron gun 17 is grounded and the cathode of the master gun is brought to a positive reference potential by the voltage source 110. The master beam control chain comprises the transformer 104, the amplifier 95, the two circuits 98 and 99 for identification of the frequencies f_1 and f_2 , the two rectifiers 100 and 101 and the vertical sweep integrator 20 which is connected in a loop by the line 37 through the amplifier 36 with the vertical deflection coils 14. This control circuit is identical with the circuit of FIG. 8 and operates on the same principle.

On the other hand, the form of construction shown in FIG. 9 provides two improvements in the embodiment of FIG. 8 and these consist on the one hand in ensuring that the luminance signal is in fact of absolutely zero value throughout the retrace period and, on the other hand, in increasing the intensity of the master beam during the last portion of the line blanking signal in order to increase the effect of position control of this latter and to carry out correct positioning of the master spot as rapidly as possible before said spot starts on the line proper. This is carried out in practice as follows: the line blanking signal 111 delivered by the transmitter is differentiated by the capacitor 112 and the second leading edge of the blanking signal shown at 221 triggers the monostable multivibrator 113 which accordingly delivers a rectangular pulse 222 having a duration which is approximately 5 percent shorter than that of the image black which follows the line blanking. The summing device 114 then applies in the appropriate direction the sum 236 of the line blanking signals 111 and the signals 222 of the monostable multivibrator 113 to the cathode of the master electron gun 17 by means of the line 223. In this manner, the master gun is completely extinguished by the high positive voltage applied to the cathode of the gun 17 during the retrace period whilst, on the contrary, the current of said master gun increases during the line entrance period as a result of the negative voltage applied, thereby increasing the gain of the control system to a considerable extent.

FIG. 10 is a schematic diagram showing another electronic circuit of improved design with respect to the circuit of FIG. 8. In this mode of execution of the invention which is again applied to a luminescent screen tube for the reproduction of color television images by means of the master electron gun 17 and three slave electron guns 50, 51 and 52, provision is additionally made for control of the horizontal scan at a strictly constant linear velocity which makes it possible to suppress distortions of the image.

There are again shown in FIG. 10 the screen 1 of the picture tube 13 and the vertical and horizontal deflection coils 14 and 16, the tube 13 being viewed from above in this figure. As in the example of FIG. 8, the screen guiding strips have two pitches having recur-

rence frequencies p_1 and p_2 and produce signals having frequencies f_1 and f_2 under the influence of the master spot. These signals are analyzed by the electromagnetic radiation detector 94 (ultraviolet radiation, for example) and are employed by means of the control loop which comprises the amplifier 95, the two tuned circuits 98 and 99, the two rectifiers 100 and 101 in opposition, the integrator 20, the amplifier 36 and the line 37 so as to produce action on the vertical deflection coils 14. The proportionality between the detected frequencies f_1 and f_2 and the linear scanning velocity of the master spot being strictly constant, it is consequently possible by maintaining one of these two frequencies at a constant value to subject the horizontal scan of the master spot on the screen to a constant rate of displacement at any given instant. This arrangement completely eliminates any distortion of the line scan by reason of the fact that each spatial interval of transversal of the beam across the screen corresponds with strict accuracy to each time interval and that, between two line blanking signals, the beam travels over a distance which is strictly constant no matter what distortions of any kind may otherwise affect the scanning device. An electronic circuit which serves to perform this function is illustrated in FIG. 10.

In the example of FIG. 10, the frequency F_1 corresponding to the theoretical value of f_1 for a scan at the desired velocity v is chosen as centering frequency.

The frequency discriminator 224 which is centered on the frequency F_1 delivers at its output a zero signal when the frequency f_1 produced by the displacement of the spot is exactly F_1 , which is either positive or negative according as the real frequency f_1 deviates to a greater or lesser extent from the centering frequency F_1 . If the real frequency f_1 decreases, for example, this arises from the fact that the spot is traveling at an insufficient velocity across the screen; the output signal of the discriminator 224 is in that case positive and increases the amplitude of the horizontal scanning device 19, for example by increasing its supply voltage; this is obtained by means of the signal delivered by the discriminator 224 which is amplified by 225, the output voltage of the amplifier 225 being added to the fixed direct-current voltage supplied by the source 226.

The horizontal scanning current derived from the device 19 controls via the line 227 the horizontal deflection coils 16 of the picture tube 13, the time constant L/R of said coils being chosen of sufficiently low value to ensure that a sufficiently fast correction can be made. Conversely, if the spot velocity is too high, the developed frequency f_1 is above the reference frequency F_1 and the supply voltage of the scanning device 19 decreases, thereby reducing the amplitude and correlatively the velocity of horizontal travel of the spot. It is therefore ensured that the spot velocity at each instant is precisely the velocity which corresponds to the theoretical frequency F_1 and that all distortion is reduced to zero. The frequency f_2 falls distinctly outside the zone of action of the discriminator 224 and does not play any part.

FIG. 11 describes an electronic circuit which applies to the device of FIG. 3 in the case in which the beam of the master electron gun is modulated at a high frequency.

In order to prevent the information on the position of the master beam derived from the conductors 11 and 12 from being disturbed by spurious signals (in particu-

lar by low-frequency transient signals) or even from coinciding with the beams of the slave electron guns, it is an advantage in accordance with the invention to modulate the beam of the master electron gun at a constant frequency. This frequency is chosen so as to be above the cut-off frequency of the video signal (6.5 Mc/s), a value of the order of 9 Mc/s, for example, being particularly recommended.

From a practical viewpoint, the circuit of FIG. 11 comprises the two transformers 140 and 141 which are located respectively on the conductors 11 and 12. The secondary circuits of the transformers 140 and 141 are tuned to the frequency of 9 Mc/s which is employed to modulate the beam of the master electron gun 17 by the oscillator 228. In this manner, virtual filtering is carried out at the level of the transformers 140 and 141 which permit transmission to the subsequent control circuit of only those signals which correspond exactly to the signals of the master beam 17. Each transformer 140 and 141 in turn supplies an amplifier, namely the amplifiers 142 and 143 respectively. These amplifiers are connected to the rectifiers 144 and 145 which are mounted in opposite directions in order to supply to the input 146 of the integrator 20 a signal which is proportional to the difference in current intensities received by the conductors 11 and 12 from the screen. This embodiment has a further advantage arising from the fact that the circuit which is common to the conductors 11 and 12 and to the two primary windings of the transformers 140 and 141 is brought to a high voltage with respect to ground (+ 25 kV, for example) and the two transformers 140 and 141 thus isolate the entire control circuit with respect to said high voltage; inasmuch as the secondary windings of the transformers 140 and 141 are grounded, the control chain also remains at ground potential. The example of FIG. 11 has been described in the case of a control obtained from the difference between the two currents of the master beam which are closed respectively on the two upper and lower guides of each guiding strip.

It is clearly understood that the foregoing description is not intended to imply any limitation and that it would not constitute any departure from the scope of the invention to employ the modulation of the master beam in conjunction with all the other modes of execution of the invention hereinbefore described (modulated strips having a pitch p_1 and p_2 , detection and formation of the error signal by means of electromagnetic radiations). In the case of the modulated strip having a pitch p_1 and p_2 , the electron gun modulation frequency is distinctly higher than the frequencies f_1 and f_2 produced by traversal of the beam across the screen and the demodulation of the modulation frequency makes it possible to revert to the control frequencies f_1 and f_2 without any difficulty.

The schematic diagram of FIG. 12 shows the manner in which the method according to the invention can be applied to a color television screen by means of only two electron guns. The first electron gun performs the function of master gun and its spot 147 travels along the guiding strip 2 which is made up of the upper and lower guides 2a and 2b respectively. There are associated with said guiding strip the three strips 2v (green), 2r (red) and 2b' (blue) of a triplet of luminescent strips. The lower portion of said FIG. 12 shows the ternary pulse sequence whereby the spot of the second beam is switched as instantaneously as possible so as to

cause this latter to pass successively from point to point and from one color strip to the strip which is immediately adjacent thereto. In the case of FIG. 12, the sequence begins at the instant of time t_0 , the guiding spot being located at 147 and the luminous spot being located at 148 on the green strip. Up to the instant t_1 at which the guiding spot is at 149, the spot of the second electron gun traverses the green strip from position 148 to position 150. From the instant t_1 , the order of switching of the spot of the second electron gun is received and at the instant t_2 the spot of said second electron gun reaches the red strip at position 151 which is very slightly displaced towards the right with respect to position 150. Said spot remains in position 152 up to the instant t_3 . The second switching order is received at this instant and enables the spot to reach position 153 on the blue strip at the instant t_4 and remains at this point until the instant t_5 corresponding to position 154. If the period of the sequence is sufficiently short so that the separating power of the eye cannot permit detection of changes of successive strips by the observer, the reproduction of the color image is correct. In the example described, the time intervals ($t_1 - t_0$), ($t_3 - t_2$), ($t_5 - t_4$) etc. are 33 nanoseconds and the switching times ($t_2 - t_1$), ($t_4 - t_3$) etc. do not exceed 3 nanoseconds. The luminance signal must obviously be switched to the corresponding chrominance signals in synchronism with the deflection of the beam itself.

FIG. 13 is an electronic circuit diagram which serves to carry out the sequences of FIG. 12. There is shown in this figure the picture tube 13 with its photoelectric cell 94 and its control loop 37 for controlling the vertical deflection plates by means of the circuit 163 for the selection and processing of the two frequencies f_1 and f_2 as already described a number of times in the foregoing. The master electron gun is designated by the reference 17 and the single slave gun is given the reference 50. Said gun 50 is equipped with two complementary deflection plates 155 having the precise function of causing the beam of the electron gun to pass very rapidly from one color strip to the other. To this end, an oscillator 156 at the frequency of 30 Mc/s controls a ternary counter 157 which opens and closes successively the three gates 158, 159 and 160 which transmit to the slave gun 50 via the line 161 the orders for switching the luminance signal to the three chrominance signals 229, 230 and 231. Moreover, the signals derived from the ternary counter 157 control the matrix device 232 which delivers as a function of the sequence the voltage which is necessary to carry out the additional vertical deflection of the slave beam via the line 162 which produces action on the deflection plates 155 so as to ensure transfer of the beam from one strip to the other.

The construction of FIG. 14 shows one of the possible arrangements of the luminescent screen in accordance with the invention as applied to the reproduction of color television images in the case of horizontal scanning with two interlaced half-fields. In this FIG. 14, there is shown diagrammatically the left portion of a television screen according to the invention in which there can be seen as in the previous examples the line entrance zone A and the luminescent zone B proper. Two horizontal guiding strips 2 and 3 are shown in this figure. A luminescent strip having a blue color, namely the strips 165 and 166 respectively are associated with

each guiding strip. Two doublets each having a red strip and a green strip are associated with each set consisting of a guiding strip and a blue luminescent strip. There can thus be seen the red strips 167, 168, 169 and 170 and the green strips 171, 172, 173 and 174. In this form of construction, the blue strip which corresponds to the range of weakest luminance is purposely narrower than the corresponding red and green strips. Scanning takes place in such a manner as to ensure that the red and green doublets located above the guiding line correspond to each even-numbered half-field whilst the red and green doublets which are located beneath the guiding strip correspond to each odd-numbered half-field; accordingly, the guiding line and the blue strip are common to the scansion of both half-fields.

Thus, at the time of an initial scan of the guiding spot 175 along the strip 2, the green and red spots having the references 176 and 177 respectively move along while scanning the strips 171 and 167 and the spot 178 travels along the blue strip 165. At the time of the following scan, the same guiding spot 175 directs the blue spot 179 along the strip 165, the red spot 180 along the strip 168 and the green spot 181 along the strip 172. It is therefore apparent that, in this form of construction, provision is made for double scanning with alternately upward and downward deviation of the red and green signals of the beam.

From FIG. 14 it is seen that the line entrance zone A is constituted in the downward direction by successive regions such as the regions 210, 211, 212 and 213 carrying blocks having pitches p_1 and p_2 in association with the pitches p_1 and p_2 of the guides of the guiding strips 2 and 3. Provision is made between two guiding strips such as 2 and 3 for two blocks such as the blocks 211 and 212 which have different pitches. The arrangement shown in FIG. 14 can readily be carried into effect by virtue of the presence of two additional deflection coils for controlling the red and green electron guns which are alone provided. Under the control of half-field identification signals, a pulse is fed into said deflection coils at each partial scan, thereby deflecting the two red and green beams to the desired extent either in the downward or upward direction.

FIG. 15 relates to another mode of scanning which is also of the interlaced type but in which two successive traverses of two halves of each image are carried out in this case by scanning respectively the even strips at the time of the initial traverse, for example, and the odd strips at the time of the second traverse. In order to make it possible for the guiding signal detection means to distinguish the even lines from the odd lines, the guiding strips have been designed in a special manner in the example of FIG. 15. In fact, the guiding strips 2, 3 and 4 which are alone visible in the figure are constituted as in some of the previous examples by two guides, namely an upper guide (2a, 3a and 4a) and a lower guide (2b, 3b and 4b). There is associated with each of said strips a color triplet, namely the triplet 182 in the case of the strip 2, the triplet 183 in the case of the strip 3 and the triplet 184 in the case of the strip 4. However, in this embodiment, the pitches p_1 and p_2 of the two upper and lower guides of each guiding strip are reversed from one strip to the next. It will in fact be observed by studying the figure that, in the guiding strip 2, the guide 2a has a pitch p_1 and the guide 2b has a pitch p_2 ; conversely, the upper guide 3a of the guiding strip 3 has a pitch p_2 and the lower guide 3b of the strip

3 has a pitch p_1 ; in the case of the strip 4, it is again the upper guide 4a which has the pitch p_1 and the lower guide 4b which has the pitch p_2 .

In the line entrance zone A, the surfaces 210, 211, 212 and 213 are made up of blocks having respective pitches p_1 , p_2 , p_1 and p_2 in conjunction with the pitches of the corresponding guides 2a, 2b, 3a, 3b, 4a and 4b.

FIG. 16 shows the diagram of the electronic circuit 10 for the practical application of the embodiment of the screen shown in FIG. 15. There again appear in FIG. 16 the main elements of the control loop which has already been described a number of times, especially in FIGS. 9 and 10, and comprises the two circuits 98 and

15 99 tuned to the frequencies $f_1 = p_1/v$ and $f_2 = p_2/v$. Two differential amplifiers designated respectively by the references 185 and 186 and having outputs connected to two AND-gates 187 and 188 are shunt-connected in the circuit of each diode 100 and 101. 20 The outputs of said gates 187 and 188 are connected to the field scanning integrator 20 which, in a manner which has been described earlier, supplies via the line 37 the vertical deflection coils 14 of the picture tube 13. The signals 191 for identification of even and odd fields are applied via the lines 189 and 190 to the second input of each AND-gate 187 and 188.

The operation of the electronic circuit of FIG. 16 is as follows: the signals which are rectified by the diodes 100 and 101 control directly the two differential amplifiers 185 and 186 which are mounted in opposition of sign, the forward and reverse inputs being crossed, that is to say in which the same difference in amplitude between the signals of frequency f_1 and the signals of frequency f_2 produces at the output of the amplifiers 185 and 186 signals which are equal but of opposite polarity. These signals are then fed into the AND-gates 187 and 188 and are combined therein with the indications 191 and 233 of the half-field identification signal, with the result that, at a given moment, one of the two AND-gates 187 or 188 is open and the other is closed. At each even-numbered field, for example, the gate 187 alone is open and the correction signal derived from the amplifier 185 has a polarity such as to cause an increase in the signal of the integrator 20, namely a downward displacement of the master-slave beams. The deviation of the master beam in the line entrance zone A accordingly corresponds to the successive positions 192, 193 and 194 and consequently results in scanning of the guiding strip 3. On the contrary, in the case of an odd-numbered field, the gate 188 is open and the gate 187 is closed. Under these conditions, the signal derived from the amplifier 186 has a polarity such as to produce a reduction in the signal of the integrator 20, that is to say a displacement of the master-slave beams towards the top of the screen; the master spot will therefore follow trajectories corresponding to the positions 192, 195, 196 and to the guiding line 2.

FIG. 17 shows a third embodiment of a color television screen for scanning by means of two interlaced half-fields. In the embodiment of FIG. 17, each guiding strip is associated with two consecutive color triplets which are each scanned at the time of one of the successive half-field sweeps. There can again be seen in this FIG. 17 the line entrance zone A and the zone B of the screen proper. The guiding strips 2 and 3 are made up of two upper and lower guides, namely the

guides 2a and 3a and the guides 2b and 3b respectively. The upper guides 2a and 3a have a pitch p_1 and the lower guides 2b and 3b have a pitch p_2 . Between the two guiding strips 2 and 3 are located two color triplets designated respectively by the references 197 and 198. 5 The line entrance zone A has surfaces 199 and 200 formed of blocks having a pitch p_1 and the surfaces 201 and 202 are formed of blocks having a pitch p_2 . The surfaces 201 and 200 correspond respectively to the color triplets 197 and 198.

At the time of an initial scansion of the color beams, the triplet 197 is swept by the three spots 203, 204 and 205; and at the time of the following half-field, the triplet 198 is swept by the spots 206, 207 and 208, thus performing a complete scan of the screen surface in two consecutive half-fields. This result is obtained in a practical manner by subjecting the master beam alone to a complementary downward deflection field, the intensity of which is variable as a function of the half-field considered, namely zero in the case of the even half-fields, and as a function of the value corresponding to the interval between two successive triplets in the case of the odd fields. At the time of the initial scansion shown at 234, 203, 204 and 205, the additional deflection field is present and the master spot is displaced downwards with respect to the slave beams or, in other words, the slave beams have been relatively displaced in the upward direction since the master spot is caused to follow the line 3. At the time of the second scansion, the additional deflection signal is suppressed and inasmuch as the master spot is again located on line 3 at 235, the slave spots follow the paths 206, 207 and 208. The signals which determine either the presence or absence of the additional deflection signal are naturally supplied by the half-field identification signals.

The frequencies f_1 and f_2 produced as above described by means of the guide strips do not need to be produced by guide strips that are interrupted at regular intervals of respective pitch p_1 from one guide strip and p_2 for the other. The guide strips may be provided in a pattern that embodies width modulation along their length, with the pattern repeating at the pitch p_1 and p_2 on the respective strips of the pair. After all, strips formed of broken segments of constant width interrupted by gaps at regular intervals are also a kind of width modulated pattern, with the width having a constant finite value for the length of the broken segments and a zero value for the length of the gaps. The term "width modulation" must therefore be used in a sense which includes discontinuous strips made up of segments of constant width interrupted by gaps.

What I claim is:

1. A method of guiding the beam of charged particles of a luminescent screen display tube, said beam being displaced under the combined action of two orthogonal deflection scans to scan the screen of said display tube in a sequence of lines distributed over the screen, said lines being traced by a spot where said beam in an unblanked state impinges on the screen, said method comprising the steps of:

deflecting the beam prior to beginning the scan of each line of said sequence to a portion of said screen beyond the display area thereof, hereafter referred to as the line entry guide area of the screen;

detecting the beam spot position relative to a continuation in said guide area of a line of said sequence,

by differential excitation by the beam of two portions of said guide area on either side of said line continuation and using a signal produced by such detection to modify the beam deflection to guide said spot towards said line continuation while the scanning movement for scanning the corresponding line begins, and

scanning said line subject to similar modification of the deflection transverse to said line pursuant to detection of differential excitation of guiding stripes on said screen on either side of said line, the effective range of deviation detectable as aforesaid and correctible by such modification being much less in case of said line than in case of the extension thereof in said line entry guide area.

2. A method according to claim 1 in which the step of detecting differential excitation is carried out to produce a signal corresponding to the differential excitation ratio rather than to an arithmetic excitation difference, which signal is then applied to modify the deflection of the beam.

3. A method according to claim 1 in which during the line scan the progress of said spot is detected by means of at least one of said guide stripes to produce a signal applied to the line scan deflection to accelerate or decelerate the scan so as to maintain the scan velocity constant.

4. A method according to claim 1 in which the step of detecting differential excitation is carried out by comparing the amplitude of two frequencies produced by the scanning of said guide stripes by said spot as the result of the respective patterns of said guide stripes in the form of width modulation along their length at two respective frequencies.

5. A method according to claim 1 which includes the step of increasing the intensity of the beam during at least part of the time the said spot is in said line entry guide area.

6. A method according to claim 1 in which a plurality of beams are deflected with the use of common deflection means to scan lines slightly displaced from each other, in which further only one of said beams is deflected in such a path that its spot impinges on said guide stripes, and in which the said modification of deflection affects all of said beams equally.

7. A method according to claim 6 in which the beam which is deflected so that its spot scans said guide stripes, is modulated at a predetermined frequency by the effect of which the excitation of said guide areas and said guide stripes by that one of said beams is distinguished from the effects of the other or others of said beams.

8. A method according to claim 1 in which that one of said beams which is deflected so that its spot scans said guide stripes, is unblanked while deflected into said line entry guide area.

9. A luminescent screen display tube having a luminescent screen including a display portion and a smaller adjacent guide portion and having at least one electron gun means for producing a deflectable electron beam for scanning said screen, said screen being provided over its entire display portion with a series of pairs of guide strips, each pair corresponding to one of the lines of a scan pattern over which the beam of one said gun of the tube is adapted to be scanned, the spacing between the two strips of a pair being smaller than the diameter of the spot produced by the impingement

of said beam on said screen, said guides being arranged to produce a detectable excitation upon impingement of said beam in proportion to the area of impingement and being patterned with a width modulation along their length to produce modulation of said excitation during scan, the width modulation of two guides of a pair being at a different pitch.

10. A luminescent screen display tube according to claim 9, wherein the upper and lower guide strips of each pair are constituted by a series of broken lines interrupted by regularly spaced gaps with a pitch that is different as between the two strips of a pair.

11. A luminescent screen display tube according to claim 9, wherein the width-modulated strips are metallic and the two guide strips of each pair are electrically connected and constitute a single electrode, whereby the fraction of the beam current containing components which are modulated at the frequencies corresponding to the scanned width modulation may be used to correct the beam deflection.

12. A luminescent screen display tube according to claim 9, wherein the width-modulated strips are formed of a substance which gives rise under the action of the spot to the emission of an electromagnetic radiation and wherein photoelectric cell means are provided in the proximity of the tube neck for selective detection of such radiation and formation of a signal therefrom.

13. A luminescent screen display tube according to claim 9, wherein the width-modulated strips are formed of a substance which gives rise under the action of the spot to the emission of a secondary-electron current and means are provided within said tube for detection of said current and obtaining a signal therefrom.

14. A luminescent screen display tube according to claim 9 for the reproduction of color television images by the three-color process, wherein the guiding strips are each associated with a triplet of three continuous horizontal and rectilinear strips of luminescent material each corresponding to one of the primary colors, and wherein the tube is provided with four electron guns in which a first gun thereof is a master gun and emits a beam impinging on said guiding strips and wherein the three other electron guns or so-called slave guns each correspond to the three primary colors and emit beams which are caused to follow the displacements of the master beam, by being subjected to common deflecting forces, so that corresponding spots move parallel to the guiding beam spot and scan with strict accuracy each of the three luminescent color strips respectively.

15. A luminescent screen display tube according to claim 14 having associated therewith means for producing magnetic scanning deflection of the beams emitted by said four electron guns and having also means for producing constant centering magnetic fields affecting said beams in such a way that said beams penetrate into the zone in which said magnetic scanning deflection is applied while proceeding as parallel as practically possible to the axis of the tube and as close as practically possible to said axis.

16. A luminescent screen display tube according to claim 9 adapted for the reproduction of color television images in accordance with the method of horizontal scanning known as interlaced scanning, wherein the guiding strips are each associated with a plurality of luminescent color strips and only some of said strips are scanned by the beams at each half-field.

17. A luminescent screen display tube according to claim 16 in which each guide strip pair is disposed in predetermined relation to two triplets of luminescent color strips such that when said guide strip pair is scanned in one half frame one of said triplets will be scanned, and when said guide strip pair is scanned in the other half frame the other of said triplets will be scanned.

18. A luminescent display apparatus including a luminescent screen tube as defined in claim 9 and also including means for deflecting said electron beam as aforesaid and means responsive to the excitation of said guides for correcting the deflection of said electron beam in a direction transverse to said scan lines, said apparatus further including means for detecting variation in frequency or phase of one of the frequencies of variation or of said detectable excitation produced by the scanning of said guides by said spot and for utilizing said frequency or phase variation to modify the deflection of said electron to make the velocity of scan more uniform.

19. A luminescent screen display apparatus including a luminescent screen display tube according to claim 9 adapted for the reproduction of color television images by the three-color process, wherein said guiding strips are each associated with a triplet of three continuous horizontal and rectilinear strips of luminescent material each corresponding to one of the primary colors, and wherein the tube is provided with two electron guns, said apparatus including means for deflecting the beams produced by said guns, means responsive to the excitation of said guiding strips by one of said guns, referred to as the master gun, for modifying the operation of said deflecting means to assure the guidance of the beam of said master gun with reference to said guiding strips and means for causing the beam of the gun other than said master gun, referred to as the slave gun, to be rapidly deflected vertically relative to the beam of said master gun, so that the beam of said slave gun may scan the three luminescent strips of said triplets in a sequence suitable for coordination with successive switching of color video signals.

20. A luminescent screen display tube having a luminescent screen including a display portion and a smaller adjacent guide portion, and having at least one electron gun means for producing a deflectable electron beam for scanning said screen, said screen being provided over its entire display portion with a series of pairs of guide strips, each pair corresponding to one of the lines of a scan pattern over which the beam of one said gun of the tube is adapted to be scanned, the spacing between the two strips of a pair being smaller than the diameter of the spot produced by the impingement of said beam on said screen, said guides being arranged to produce a detectable excitation upon impingement of said beam such that the excitation of one guide of a pair can be distinguished from that of the other guide of said pair, said guide area of said screen being adjacent to its display area along a boundary to which the ends of all the scan lines of said display area begin, said guide area of said screen including principally pairs of guide zones such that each member of a pair of said zones is separated by the extension of a scan line into said guide area of said screen, said guide zones being arranged to provide a detectable excitation when said beam impinges thereon which is not distinguishable from that of the adjacent guide stripe, but is distin-

guishable from that produced by the guide stripe just across said scan line from said adjacent guide stripe.

21. A luminescent screen display tube according to claim 20 in which said guide stripes and said guide zones are discontinuous in the direction of the adjacent scan line, in the sense that there are gaps in which the presence of the spot of said beam does not produce the aforesaid detectable excitation produced by the presence of said spot on other portions of said guide stripes and guide zones, and in which said gaps are provided at regular intervals in the direction of said scan line with a pitch on one side of said scan line or its extension in said guide area different from the pitch of said gaps on the other side of scan line or its extension in said scan area.

22. A luminescent screen display tube according to claim 21 adapted for the reproduction of color television images in accordance with the method of line scanning known as interlaced scanning, wherein the aforesaid guide strips are so provided that adjacent pairs of guide strips have a reversed relation of the relative characteristics of the strips of the pair.

23. A luminescent screen display tube according to claim 20 for the reproduction of color television images by the three-color process, wherein the guiding strips are each associated with a triplet of three continuous horizontal and rectilinear strips of luminescent material each corresponding to one of the primary colors, and wherein the tube is provided with four electron guns in which a first gun thereof is a master gun and emits a beam impinging on said guiding strips and wherein the three other electron guns or so-called slave guns each correspond to the three primary colors and emit beams which are caused to follow the displacements of the master beam, by being subjected to common deflecting forces, so that corresponding spots move parallel to the guiding beam spot and scan with strict accuracy each of the three luminescent color strips respectively.

24. A luminescent screen display tube according to claim 23 having associated therewith means for producing magnetic scanning deflection of the beams emitted by said four electron guns and having also means for producing constant centering magnetic fields

affecting said beams in such a way that said beams penetrate into the zone in which said magnetic scanning deflection is applied while proceeding as parallel as practically possible to the axis of the tube and as close as practically possible to said axis.

25. A luminescent screen display apparatus including a luminescent screen display tube according to claim 23 adapted for the reproduction of color television images by the three-color process, wherein said guiding strips are each associated with a triplet of three continuous horizontal and rectilinear strips of luminescent material each corresponding to one of the primary colors, and wherein the tube is provided with two electron guns, said apparatus including means for deflecting the beams produced by said guns, means responsive to the excitation of said guiding strips by one of said guns, referred to as the master gun, for modifying the operation of said deflecting means to assure the guidance of the beam of said master gun with reference to said guiding strips and means for causing the beam of the gun other than said master gun, referred to as the slave gun, to be rapidly deflected vertically relative to the beam of said master gun, so that the beam of said slave gun may scan the three luminescent strips of said triplets in a sequence suitable for coordination with successive switching of color video signals.

26. A luminescent screen display tube according to claim 20 adapted for the reproduction of color television images in accordance with the method of horizontal scanning known as interlaced scanning, wherein the guiding strips are each associated with a plurality of luminescent color strips and only some of said strips are scanned by the beams at each half-field.

27. A luminescent screen display tube according to claim 20 in which each guide strip pair is disposed in predetermined relation to two triplets of luminescent color strips such that when said guide strip pair is scanned in one half frame one of said triplets will be scanned, and when said guide strip pair is scanned in the other half frame the other of said triplets will be scanned.
